VARIABLE TRANSFORMER PICK-OFF

Fred P. Strother, Minneapolis, and Bert A. Coss, St. Louis Park, Minn., assignors to Minneapolis-Honeywell Regulator Company, Minneapolis, Minn., a corporation of Delaware

Application September 24, 1945, Serial No. 618,180

4 Claims. (Cl. 171—119)

1

Our invention relates to variable transformer pickoffs and particularly to transformer pickoffs or control devices in which a feeble actuating force is utilized to produce an amplified controlling force or electric current.

Another object of the invention resides in providing a pickoff in which a substantial signal may be had at the vicinity of the zero setting of the actuating member.

A still further object of the invention resides in providing a pickoff using a magnetic circuit and in which the reluctance of the magnetic circuit remains substantially constant throughout the entire range of operation of the device.

Another object of the invention resides in providing a pickoff in which no appreciable counter magneto motive force is produced to load the device.

A feature of the invention resides in providing a device in which the movement of the movable actuating member is damped so as to quickly bring the actuating member back to rest.

An object of the invention resides in providing a pickoff including a coil having a core of non-magnetizable material and a core structure having two air gaps traversed by opposite magnetic fields at certain instants and in arranging the coil so that the flux from both of the poles passes through the core of the coil and in further mounting the coil for movement so that the proportion of the fluxes intercepted varies in accordance with the position of the coil relative to the poles.

Another object of the invention resides in providing a pickoff having a magnetic circuit including a core formed with an air gap and in further providing a coil movable in said air gap and having its inside dimension in the direction of its movement equal to the corresponding dimension of the core at the air gap.

A feature of the invention resides in constructing the dimensions of the core of the coil in the direction of movement thereof substantially equal to the distance between the outermost edges of said pole faces in the same direction.

Other objects of the invention reside in the novel combination and arrangement of parts and in the details of construction hereinafter illustrated and/or described.

In the drawings:

Fig. 1 is a wiring diagram of an electric control system illustrating an embodiment of our invention.

Fig. 2 is a longitudinal elevational section view of the control device utilized with the system disclosed in Fig. 1.

Fig. 3 is a plan sectional view taken on line 3—3 of Fig. 2.

Fig. 4 is an elevational sectional view taken on line 4—4 of Fig. 2.

2

Fig. 5 is a wiring diagram of the damping device of the invention.

The variable transformer pickoff or control device shown in Figs. 2, 3 and 4 comprises a frame 10 formed of heavy metal which is bent to provide a base 11 and spaced uprights 12 and 13. The upright 13 has a flange 14 extending outwardly therefrom which serves a purpose to be presently more fully described.

Attached to the upper end of the upright 12 is a tubular housing 15 which has a bore 16 therein. In this bore are mounted two ball bearings 17 and 18 which rotatably support a shaft 19. The movable actuating member of the device which is designated by the reference numeral 30 is carried by the shaft 19. This actuating member comprises a hanger 20 which is attached to said shaft at the end thereof located between the uprights 12 and 13. The hanger 20 has attached to the lower end thereof by means of screws 22 an insulating mounting 21. The mounting 21 is formed with a rectangular opening 23 in which is mounted a coil 24 of suitable insulated wire. The ends of this coil are connected by means of suitable pigtails not shown with binding posts or other terminals by means of which the said coil may be connected in the desired circuit. The coil 24 is held within the opening 23 by means of two thin sheets 25 and 26 of insulating material which are secured to the mounting 21 by rivets 27. The coil 24 is so constructed that the same has a central opening 28 therein which is rectangular in form and of an appreciable width as shown in Fig. 4. Said opening gives the coil 24 a core which consists principally of air and of the insulating material of the sheets 25 and 26 overlying the coil. Said coil thus has a core of non-magnetizable material.

The coil 24 is mounted for movement within an air gap 29 formed in a core structure 31. The core structure 31 includes a U-shaped core member 32 having two spaced legs 33 and 34 and a connecting portion 35 at one end of each of said legs. The other ends 36 and 37 of the core member 32 form poles which have pole faces 38 and 39 extending outwardly therefrom and lying substantially in a common plane.

The core member 32 is supported in the following manner: Overlying the flange 14 of frame 10 is an angle member 46 which has a base 47 resting upon said flange and an upright leg 48 extending upwardly from said base. Both the base 47 and the flange 14 have elongated slots 49 in the same and through which bolts 51 extend. By means of this construction, the upright leg 48 of the angle member 46 may be moved toward and from the upright 12 of frame 10. The connecting portion 35 of the core member 32 lies against the portion 48 of the angle member 46 and is held

attached thereto by means of two screws 52. These screws extend through a bar 53 overlying the connecting portion 35 of the core member 32 and are threaded into the leg 43. The two legs 33 and 34 of the core member 32 have windings 54 and 55 mounted thereon which are so energized as to create a continuous magneto field directed out of one pole face and into the other. The device operates in a manner to be presently more fully described.

The air gap 29 lies between the two pole faces 38 and 39 and the face 41 of another core member 42. The core member 42 is in the form of a laminated bar and is imbedded in a block 43 of insulating material. This block overlies the upright 12 and is secured thereto by means of a number of screws 44 which pass freely through said upright and are threaded into said block. Other screws 45, threaded in the upright 12, engage the rear surface of the block 43 and serve to adjust the core member 42 with reference to the pole faces 38 and 39 of the core member 32.

It will be readily comprehended from the drawings that the coil 24 is disposed within the air gap 29 and that the same swings in a plane at right angles to the direction of extent of said air gap. It will be noted that the width of the opening in the coil 24 which becomes the core for said coil is substantially equal to the width of the core member 42 and is also substantially equal to the distance between the extreme edges of the pole faces 38 and 39. By means of this construction, the magnetic field caused by energization of coils 54 and 55 passes from one pole face of core 32 across air gap 29 through bar 42 and back across the air gap to the other pole face, completing its path through core 32. When coil 24 is in its normal position, shown in Figs. 3 and 4, there is little magnetic linkage between the coil and the fields established across the gaps, and such linkage as takes place have equal and opposite effects on the coil. When, however, the coil is shifted to either side by swinging the same on the axis of the shaft 19, the linkage with one of the fields is increased while that with the other field decreases. The resultant effective linkage induces an alternating voltage in the pickup coil 24 which is of one phase or the opposite phase, depending on the direction in which the pickup coil is moved. For displacement of the pickup coil usual to one the width of the pole face, the signal is proportional to the amount of displacement.

The actuating member 30 has a pendulum action when moved by a yieldable force. To bring the said member rapidly to rest after the same has been moved, a damping device 61 is employed which is best shown in Figs. 2 and 4. This device comprises a core structure 62 which includes a bar 63 having a number of legs 64 and 65 projecting outwardly therefrom. The bar 63 is rigidly secured to the block 43 of insulating material by means of screws not shown. Mounted on the legs 64 are windings 67 which are connected in a manner to be presently described. Operating in conjunction with the core structure 62 is another core structure 69 identical therewith. This core structure has a bar 69 and legs 71 extending outwardly therefrom and corresponding to the legs 64. Mounted on these legs are windings 72 which correspond with the windings 67. Other legs, similar to the legs 65 are also provided for the core structure 69, so that air gaps 73 are formed between the legs of the two core structures. In the air gaps 73 is movably positioned an arcuate conductor 74 which is attached to the

insulating mounting 21 of actuating member 20 by means of screws 75. These screws pass through an ear 76 on the said conductor and through a spacer 77 and are threaded into the mounting 21. The conductor 74 travels in the various air gaps 73 and when the core members 62 and 69 are energized, set up eddy currents which retard the movement of the actuating member 30 to which the said conductor is attached and rapidly 10 bring said actuating member and the coil 24 to a stationary position. For the purpose of adjustment, the core structure 62 is mounted on the upright 13 by means of screws 81 and 82 which function in the same manner as the screws 44 15 and 45 which attach the block 43 to the upright 12.

While our invention has many uses, the same is particularly adapted to be connected in a system whereby a feeble control force may be converted into a substantial operating force. One such system is shown in Fig. 1. In this system, energization is derived from an alternating current line AC having two conductors 91 and 92 connected to the primary 93 of a transformer 94. The transformer 94 has a first secondary winding 95 center tapped at 96 and a second secondary winding 97. The secondary 97 is connected by means of conductors 98 and 99 with the two windings 54 and 55 of the control device proper. The coil 24 of this control device is connected by means of conductors 101 and 102 with a variable resistance 103. The conductor 102 is also grounded. Resistance 103 has a tap 104 which is connected by means of a conductor 105 with the grid 106 of a thermionic tube 107. The plate 109 of this tube is connected by means of a conductor 111 with one side of a condenser 112. The conductor 111 is also connected to a resistance 113 which is connected in series to a source of voltage 114. This voltage is grounded as indicated at 115. The other side of the condenser 112 is connected by means of a conductor 116 with the grid 117 of another thermionic tube 120. The conductor 119 connects the conductor 116 with a resistance 118 which is grounded. The conductor 118 has a branch 121 which is connected to the grid 122 of another thermionic tube 123, so that the output from the tube 107 feeds to both of tubes 120 and 123. The plate 124 of the tube 123 is connected by means of a conductor 125 with one side of the transformer secondary 95. The plate 126 of tube 123 is similarly connected by means of a conductor 127 with the other side of the secondary 95. The cathodes of all of the tubes 107, 120 and 123 are grounded and may be heated in any desirable manner. The tube 107 and associated elements provide a stage of amplification for the signals produced in the coil 24. It will be readily comprehended, however, that additional stages may be employed if desired.

For utilizing the amplified signal from the coil 24, an electric motor 131 is employed. This motor is of the reversible type and may consist of a rotor 132 and two windings 133 and 134 associated therewith. The winding 133 is at all times energized by conductors 135 and 136 which are connected to the conductors 88 and 99 leading from the transformer secondary 97. A condenser 137 is connected in the circuit in series with the winding 133. The winding 134 is connected at one end by means of a conductor 138 with center tap 96 of the secondary 95 of transformer 94. The other end of the winding 134 is grounded. A condenser 139 is connected across the winding 134. Winding 134 operates in a manner such that

when the current through the conductor 138 changes phase by 180°, the motor 131 reverses its direction of operation and when current in said conductor is zero, the motor stops.

The manner of connecting up the damping device 61 is shown in Fig. 5. Each of the coils 67 is connected at one end to a common conductor 141 and at its other end to a common conductor 142. These conductors are in turn connected to the conductors 143 and 144 of a direct current line DC. One end of each of the windings 72 is similarly connected to a conductor 145 which is connected to the conductor 143 and the other ends of these windings are connected to a common conductor 146 which, in turn, is connected to the conductor 144 of the line DC. In this manner, direct current is supplied to the various windings 67 and 72, causing flux to flow in the core structures 62 and 63 through the air gaps 73. This flux passes through the conductor 74, producing eddy currents therein. These eddy currents produce a drag on the actuating members 20 which bring the coil 24 rapidly to a stationary position.

The operation of the invention is as follows: Assume that the shaft 19 is to be connected to a thermometer for indicating the temperature in a room and that the motor 131 is connected by suitable gearing or other transmission to the shaft of a damper controlling the operation of a heater for heating the room in which the thermometer is located. In such an association, a call for heat by the thermometer would swing the shaft 19 and move the coil 24 out of its normal position. The fluxes from the two pole faces 38 and 39 intercepted by the coil 24 would then be different and a voltage would be set up in the coil. This voltage would be amplified through the tube 107 and impressed upon the two tubes 120 and 123. A voltage would then be impressed upon the winding 134 of motor 131, which voltage would depend upon the phase of the voltage of coil 24 produced by shifting said coil from its normal position. Motor 131 would, of course, be connected in a manner such that rotation of the same as produced by shifting of the coil 24 in the direction specified would cause the damper to move in a direction to procure more heat. If the coil moved in the opposite direction, the phase of the voltage across the winding 134 would reverse and the motor would operate in the opposite direction.

The advantages of our invention are manifest. The device is particularly adapted to installations where a pivoted operating member is desired. Since the core of the actuating coil is of non-magnetizable material, the back torque is negligible and the reluctance of the device remains the same for all positions of the actuating member. With our invention, a good zero signal is procured. The movable member comes back to stationary position in an exceedingly short time without affecting the sensitivity of the device.

Changes in the specific form of our invention, as herein described, may be made within the scope of what is claimed without departing from the spirit of our invention.

Having described our invention, what we claim as new and desire to protect by Letters Patent is:

1. In an electrical control device, a core structure including first and second core members of magnetizable material in near abutting relationship having spaced fixed air gaps defined therebetween by the extremities of said first core member in proximity with said second core member lying in the same plane, means for maintain-

ing opposite alternating magnetic fields across said air gaps, a hollow inductor rectangular in cross-section mounted for movement transversely across said air gaps, the length of the hollow portion of the cross-section of said inductor being greater than the overall distance between the extremities of said first core member lying in the same plane, and means guiding said inductor for transverse movement to vary the portions of the field of one of said air gaps which traverses said inductor whereby an alternating voltage is induced in said inductor which is variable in phase and magnitude.

2. In a control device, a coil, a core structure of magnetic material including two core members in near abutting relationship having an air gap therein for the reception of said coil, means for maintaining opposite alternating magnetic fields across said air gap, pivot means having its axis parallel with the direction of extent of said air gap for guiding said coil for swinging movement transversely of said air gap, from a neutral position of said coil, said coil encircling said air gap at said neutral position and having variable portions of said magnetic field in a particular direction traversing therein as said coil is moved from said neutral position in either direction.

3. In an electrical control device, a coil, a core structure of magnetizable material including two core members in near abutting relationship having a fixed air gap therein for the reception of said coil, means for maintaining equal and opposite alternating magnetic fields across said air gap, means for guiding said coil for movement transversely of said air gap from a neutral position in a plane at right angles to the direction of the extent of said air gap, said coil encircling said air gap in said neutral position, a planiform conductor carried by said coil and lying in a plane parallel to the plane of movement of said coil, and magnetic means associated with said conductor for dampening the movement of said coil.

4. In an electric control device, a magnetic core structure including a first and second core member in near abutting relationship, one of said core members having a pair of spaced pole pieces thereon projecting toward the other of said core members to define a pair of fixed air gaps spaced from each other, means for maintaining opposite alternating magnetic fields in said air gaps, a coil simultaneously encircling both of said air gaps in a normal position and being normally disposed in proximity to opposite edges of said air gaps with the central axis of said coil extending between said air gaps, and means for supporting said coil for movement in said air gaps and in a direction transversely thereof.
